UNITED STATES PATENT OFFICE.

ISAAC J. KILBURN, OF DENVER, AND JOHN T. DOYLE, OF BROOMFIELD, COLORADO.

CATTLE GUARD.

Application filed October 7, 1927. Serial No. 224,618.

Our invention relates to cattle guards for railways and its primary object is to provide a guard of simple construction which is easily applied to the ties of a railway 5 track and which provides a substantial, durable and efficient safeguard against cattle crossing or passing along the track.

A guard made according to our invention may be applied at opposite sides of a 10 highway and positively prevent the escape of cattle from the fields and from the highway onto the tracks.

The guard in its preferred form is composed of six sections secured to the ties 15 between and at opposite sides of the track and formed to provide two series of inclined surfaces between and over the ties. These surfaces give no foothold to the cattle and the animals are in consequence prevented 20 from crossing or passing along the track.

An embodiment of the invention thus briefly described, is illustrated in the accompanying drawings in which like characters 25 designate corresponding parts in all the views and in which

Figure 1 represents a plan view of a portion of a railway track showing our improved cattle guard in its operative position,

Figure 2, a side elevation of the track looking in the direction of the arrow A in Figure 1, and

Figure 3, an enlarged transverse section of 35 the track taken on the line 3—3, Figure 1.

The rails 5 of the track are laid as usual on ties 6, spaced the required distance apart. At the portion of the track at which the cattle guard is applied, two ties 7 alternate with the others are reduced in height 40 and fastened upon these lower ties are chairs 8 for the rails.

The chairs as best shown in Figure 3, have integral ridges 8^a for the abutment of the 45 outer flanges of the rails, and they are provided with clamp plates 9 that engage the inner flanges of the rails. The plates are held in place and are drawn downwardly to clampingly engage the flanges of the ties, 50 by bolts 10.

The chairs having bottom flanges that are apertured to receive the bolts or spikes 12 by which the chairs are fastened to the ties and their sides slant upwardly to increase their rigidity and stability in use.

The cattle guard in its preferred form,

comprises two series of sections 13 and 14 of uniform length, placed one behind the other along the track. The sections of each series consist of plates made of steel or other suitable metal bent at their ends to provide oppositely projecting parallel flanges 15.

The flanges are bent at an acute angle to the body portions of the plate so that when the flanges are fastened in engagement with the upright sides of two of the railway ties their body portions will extend slantingly with reference to the horizontal.

In the construction shown in the drawings, the sections of the guard are fastened to alternate ties 6 of regular form and supported upon the low ties 7 between the others. The flanges of the sections engage corresponding sides of the ties to which they are fastened by bolts 16, so that the sections 70 at their uppermost ends extend across the ties. The two series of sections are placed successively with their adjacent flanges fastened one above another upon the same face 75 of the same tie.

The sections of the series are arranged between and at opposite sides of the rails of the railway track in parallel relation to each other, the middle section 13 being of a width corresponding to the distance between the rails and the outer sections 14 being narrower so as to cover the end portions of the ties outside the rails.

It will be apparent that the arrangement of sloping plates between and over the ties 80 as shown in the drawings and hereinabove described provides an efficient, practical and very simple guard to prevent cattle from crossing or passing along a railroad track.

Having thus described our invention, what 85 we claim and desire to secure by Letters Patent is:—

1. The combination with a railway track having alternate ties of reduced height, of a cattle guard comprising a plate slanting 100 between alternate ties of regular height and across the tie of reduced height.

2. The combination with a railway track having alternate ties of reduced height, of a cattle guard comprising a plate slanting 105 between alternate ties of regular height and supported on the tie of reduced height.

3. The combination with a railway track having alternate ties of reduced height, of a cattle guard comprising a plate slanting 110 between alternate ties of regular height and across the tie of reduced height, and chairs

- on the intermediate tie, supporting the rails of the track.
4. The combination with a railway track having alternate ties of reduced height, of a cattle guard comprising a plate slanting between alternate ties of regular height and across the tie of reduced height, and chairs on the intermediate tie, supporting the rails of the track, each chair having a ridge for abutment of a flange of the rail, and a clamp plate engaging the opposite flange of the rail.
5. The combination with a railway track, of a plate having its ends bent oppositely and at acute angles to provide flanges for its connection to ties of a railway track, the flanges engaging corresponding sides of two ties whereby the plate extends slantingly from one of the ties to and over the other tie.
6. A cattle guard comprising in combination with a railway track of standard construction, a flanged plate slanting from a face of a tie of the track across two following ties, the plate having its flanges fastened

upon corresponding faces of the outer ties and the intermediate tie being reduced in height and providing a support for the plate, and chairs on the intermediate tie, supporting the rails of the track above the same.

7. A cattle guard comprising in combination with a railway track of standard construction two sections following one another in unbroken succession, each section comprising a flanged plate slanting from a face of a tie of the track across two following ties, the plate having its flanges fastened upon corresponding faces of the outer ties, and the intermediate tie being reduced in height and providing a support for the plate, and the adjacent ends of the plates of the two sections being fastened upon the same face of the same tie, and chairs on the intermediate ties of the sections, supporting the rails of the track above the same.

In testimony whereof we have affixed our signatures.

ISAAC J. KILBURN.
JOHN T. DOYLE.
